(57) **CLAIM**

I claim the ornamental design for an extension mount for a flat panel monitor, as shown and described.

DESCRIPTION

FIG. 1 is a perspective view of the extension mount for a flat panel monitor showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an operational rear view of the extension mount for a flat panel monitor, wherein the extension mount extends straight between a base on a wall and a flat panel monitor; and,

FIG. 9 is another operational rear view of the extension mount for a flat panel monitor, wherein the extension mount extends straight between a stand and a flat panel monitor. The broken lines are shown for illustrative purposes only and form no part of the claimed design.
